(57) **CLAIM**

The ornamental design for a fluidized bed granulation coater, as shown and described.

DESCRIPTION

FIG. 1 is a right side perspective view of a fluidized bed granulation coater;

FIG. 2 is a left side perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

A fluidized bed granulation coater has a cylindrical processing container that contains powder and particles serving as raw material, and carries out desired granulation and coating processing and the like.
